UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 21,430, dated March 29, 1892.

Application filed January 20, 1892. Serial No. 418,705. Term of patent 7 years.

To all whom it may concern:

Be it known that I, HERMAN IHLENBURG, a citizen of the United States, and a resident of Philadelphia, Pennsylvania, have invented a 5 Design for a Font of Printing-Type, of which the following is a specification.

My design for a font of type is fully illustrated in the accompanying typographical impression.

- 10 The leading feature throughout the design of the upper-case letters is the zigzagging of part of the vertical members of a number of the letters and the peculiar curve given to others.
- 15 The single vertical members of the letters "B," "D," "F," "I," "J," "K," "L," "P," "R," and "U," the left-hand vertical members of the letters "H" and "N," the right-hand vertical members of the letter "U," and the central vertical members of the letters "M" and "W," have short zigzagged portions. There is also a like configuration of the left-hand

inclined members of the letter "A," of one of the inclined members of the letter "X," and of the inclined member of the letter "Z." The 25 outside members of the letter "M" are curved outward at the bottom, and the outside members of the letter "W" are curved inward at the top. The letters "C," "E," "G," and "T," are formed of sweeping curves. These curves 30 are carried out to a less extent in a number of the other letters, the whole giving an odd effect.

I claim—

The design for a font of ornamental type, 35 as described, and as shown in the accompanying typographical impression.

In testimony whereof I have signed my name to this specification in the presence of two subscribing witnesses.

HERMAN IHLENBURG.
